DESIGN FOR A SOLVENT RECOVERY MACHINE

Clarence F. Dinley, Detroit, Mich., assignor to
Detrex Corporation, Detroit, Mich., a corpora-
tion of Michigan

Application July 8, 1947, Serial No. 140,150

Term of patent 14 years

(Cl. D49—1)

To all whom it may concern:

Be it known that I, Clarence F. Dinley, a citizen of the United States of America, residing at Detroit, in the county of Wayne and State of Michigan, have invented a new, original, and ornamental Design for a Solvent Recovery Machine, of which the following is a specification, reference being had to the accompanying drawing, forming part thereof.

Fig. 1 of the drawing represents a perspective view of a solvent recovery machine, showing my new design;

Fig. 2 represents a top plan view of the same; and

Fig. 3 represents a side elevation of the same.

I claim:

The ornamental design for a solvent recovery machine, as shown.

CLARENCE F. DINLEY.
